CLAIM

The ornamental design for a protective case, as shown and described.

DESCRIPTION

FIG. 1 is a front perspective view of a protective case.

FIG. 2 is a back perspective view thereof.

FIG. 3 is a top plan view thereof.

FIG. 4 is a bottom plan view thereof.

FIG. 5 is a left side view thereof.

FIG. 6 is a right side view thereof.

FIG. 7 is a front view thereof; and,

FIG. 8 is a back view thereof.

The broken lines represent environment and the boundary line represents the boundary of the claim. Neither of which form any part of the claim.
